UNITED STATES PATENT OFFICE.

KRISTIAN RASMUSSEN, OF BUFFALO, NEW YORK.

FUEL-OIL INJECTION PUMP.

Application filed August 31, 1927. Serial No. 216,619.

This invention relates to improvements in fuel oil injection pumps for use with oil burning engines and its principal object is to provide a greatly simplified structure which will be certain and reliable in its operation.

For the attainment of this object the invention proposes a pump structure which has a single double acting valve element as contrasted with the several structurally independent valve elements of prior devices and which, if desired, may be fitted directly to the cylinder, replacing the usual check valve mechanism at the cylinder inlet.

15 A further object is to provide an injector pump having the valve characteristics described wherein the operation of the valve element may be regulated as desired with respect to the beginning and cessation of the injection and may be automatically regulated with respect to the duration of the injection, thereby to enable regulation of the injection in accordance with the speed and load of the engine.

20 Another object is to provide in connection with an injector pump as above generally described a simple and reliable controlling mechanism operated from the crank shaft of the engine.

25 The invention is illustrated in the accompanying drawings in which:

Figure 1 is a vertical sectional view of the injector pump.

Figure 2 is a top plan view thereof.

30 Figure 3 is a sectional view showing an alternative detail consisting of a casing made in telescopic sections for the protection of the pump plunger and cylinder.

Figure 4 is a sectional view showing one form of operating mechanism for the pump.

Figure 5 is a horizontal section on the line 5-5 of Figure 4.

Figure 6 is a vertical section on the line 6-6 of Figure 4.

45 Figure 7 is a sectional view showing an alternative form of operating mechanism for the pump.

Figure 8 is a plan view of the same.

Figure 9 is a sectional view on the line 50 9-9 of Figure 7.

Figures 10 and 11 are sectional views on the lines 10-10 and 11-11 of Figure 8.

The pump consists of a suitable body or casing 20 having an oil inlet passage 21, an oil discharge passage 22 and a valve chamber 23 through which the oil flows from the

passage 21 to the passage 22, such flow being induced by the pump 24 and controlled by the valve 25. The pump 24 includes a cylinder 26 suitably fitted to the body or 60 casing 20 with its inner end communicating with the valve chamber 23 by a passage 27 which forms an axial continuation of said cylinder. The pump is completed by a plunger 28 having externally of the pump cylinder an operating head 29, the inward movement of the plunger being effected by the operating mechanism to be later described and its outward movement being effected by a helical spring 30. If desired the 70 pump may be protected by the telescoping casing shown in Figure 3 and consisting of an element 31 which is secured to the body 20, and a movable element 32 of cup-like form which fits over the element 31, bears 75 against the head 29 and receives the thrust of the operating mechanism, the element 32 having an air and oil vent 33.

The valve chamber 23 is formed at its lower end with the valve seat 34 and at its 80 upper end with the valve seat 35. As shown and preferred, the valve seat 35 is formed on a distributing member 36 separably fitted in the body 20 and having an angular passage 37 communicating with said seat and 85 with the inlet passage 21. The passage 37 opens to an annular groove 37a in the outer face of the member 36 whereby said member is operative in any position in which it may be fitted. The valve element 25 is formed 90 at its lower end with a valve face 38 for cooperation with the seat 34 and at its upper end with the valve face 39 for cooperation with the seat 35.

The valve element is preferably also 95 formed along its body with projecting guide lugs 40 which center it in and space it from the cylindrical wall of the chamber 23. For the purpose of its operation the valve element is provided with an axially extending 100 stem 41 which operates in a suitable gland or box 42 and projects beyond the casing 20. Said stem is provided at its upper end with a head 43 coacting with the operating mechanism to effect the upward movement of the valve element and with a helical spring 44 to effect the downward movement of said element, the spring bearing against a suitable abutment 45 secured to the casing.

During the outward movement of the 110 plunger 28 the valve element is in its lower position with its valve face 38 upon the seat

34, whereby to close the passage 22 and at such time oil is drawn through the usual supply pipe (not shown) and the passages 21 and 37 into the chamber 23. During part 5 of the inward movement of the plunger 28 the valve element is in its upper position with its face 39 upon the valve seat 36. At such time the oil previously drawn into the chamber 23 is forced through the passage 22 and thence to a cylinder of the engine. The valve element 25 moves to its lower position before the inward stroke of the plunger 28 is completed and thereupon the oil yet remaining in chamber 23 is forced through 10 the valve seat 36 and angular passage 37 to the passage 21, this action corresponding to that of the by-pass valve with which the prior devices have been equipped.

The pump body may be located at a distance 20 from the engine cylinder and connected to it by a pipe, the form shown in Figure 1 providing for such a pipe connection by means of a threaded recess 46 in the pump body at the discharge end of the passage 22; or the pump body may communicate directly with the combustion chamber by arranging the inlet of the latter as a continuation of the passage 22, such an arrangement being shown in Figure 4.

30 Referring to Figures 4, 5 and 6:

In these Figures I have illustrated a simple form of operating mechanism, the movements of which are derived from a shaft 47 and cam 48, the shaft 47 being driven by 35 any suitable means (not shown) from the crank shaft of the engine. For the operation of the plunger 28 a lever, designated generally as 49, is provided, said lever being mounted upon an arbor 50 and having a depending arm 51 terminating between and at 40 all times bearing upon the cam 48 and the plunger head 29.

The engagement of the arm 51 by the rise 45 of the cam 48 operates the plunger inwardly on its fuel injection stroke; and on the engagement of the arm 51 by the recession face of the cam the spring 30 operates the plunger 28 on its outward stroke during 50 which a charge of oil is drawn into the chamber 23.

The lever 49 includes an upwardly extending arm 52 to which is pivoted a horizontal arm 53. The valve element 25 is raised by a lever 54 pivoted eccentrically upon a rotatable adjustable arbor 55. The lever 54 is operated by the arm 53. For this purpose said lever has at its pivot end an upwardly projecting tooth 56 and the arm 53 has a downwardly projecting tooth 57, the rear 55 faces of these teeth being inclined whereby upon the inward movement of the arm 53 the tooth 57 may ride over the tooth 56. To insure the proper engagement of the tooth 57 with the tooth 56 a light retractile spring 60 may be connected to the end of the arm

53 and to the body 20. To permit the continued movement of the tooth 56 after the valve element has reached its upper position and the movement of the engaging end of the lever 54 has stopped, said lever is made 70 with a certain degree of springiness or resiliency.

To effect the disengagement of the tooth 57 from the tooth 56 and the consequent release of the lever 54 and closure of the valve element 25 on its lower seat by the spring 44, the arm 53 carries a projecting pin 59 and the lever 49 is formed with a horizontally projecting arm 60 which extends below the pin 59 and at a period of the movement 80 of the lever 49 engages said pin to lift the arm 53 relatively to the tooth 56 to a point where the tooth 57 will present no obstruction to the downward movement of the lever 54.

The pin 59 is preferably fitted for axial adjustment and by such adjustment the timing of the release of the lever 54 may be effected as desired. The arm 53 near the end remote from its pivot engages a stop by which its downward movement is limited. This stop is preferably in the form of a cam 61 which is mounted upon an arbor 62 connected by any suitable means (not shown) to the usual governor. By the movement of such cam from the governor the duration of the injection period may be automatically regulated, an upward movement of the cam giving an injection of shorter duration, and a downward movement giving an injection of longer duration; and in this way the power of the engine is automatically regulated. By the adjustment of the eccentric 55 with reference to its pivotal axis, the point at which the injection commences may be varied.

The drawings assume a clock-wise movement of the operating cam 48 and the operation is generally as follows:

The lever arms 51 and 52 of course move 110 in opposite directions and when the arm 51 moves to the left effecting an inward movement of the plunger, the drawings being considered, the arm 52 moves to the right effecting an outward movement of the arm 53. During such outward movement and at a point determined by the adjustment of the eccentric 55, the tooth 57 of the arm 53 engages the tooth 56 of the lever 54 and raises the latter, thus lifting the valve element 25 115 to its upper position wherein it closes against the upper seat and uncovers its lower seat.

The inward movement of the plunger being continued the oil in the chamber 23 is forced through the discharge passage 22 and thence to the engine cylinder. The injection thus effected is continued until the arm 53 is lifted in the manner described to disengage the tooth 56 and release the lever 54 whereupon the spring 44 moves the valve element 120

to its lower position wherein the passage 22 is cut off from the valve chamber and the angular passage 37 is open to said chamber. If now the inward movement of the plunger 23 continues the oil remaining in the chamber 23 will be forced back into the passage 21. These operations having taken place, the receding face of the cam engages the end of the arm 51 whereupon the lever 49 is operated in the reverse direction by the spring 30 as it effects the outward movement of the plunger 29. During such outward movement a charge of oil is drawn into the chamber 23. The arm 53 at the same time is moving inwardly i. e. to the left, the drawing being considered, and during its inward movement the tooth 57 rides over and snaps past the tooth 56 of the lever 54 and is ready to engage the same during the next reverse movement of the arm 53.

Referring to Figures 7 to 11:

In these Figures I have illustrated an alternative form of operating mechanism wherein the movements of the parts are produced by two cams 63 and 64 mounted upon a shaft 47^a which is driven from the crank shaft of the engine. The cam 63 cooperates with a lever 65 mounted upon an arbor 66 and having an upper arm 67 which is engaged by said cam and a lower arm 68 which engages the plunger head 29. The lever 65 and cam 63 are thus employed for the operation of the plunger 28. The valve stem head 43 is engaged by an operating lever 54^a pivotally mounted on a pin 69 and having beyond said pin an upward extension 70 which is engaged by the cam 64. The pin 69 is mounted on an arm 71 in turn eccentrically mounted, as at 72, the arbor of the eccentric 72 being preferably connected by suitable means (not shown) to the usual governor.

At the lower side of the eccentric 72, the arm 71 carries an adjustable horizontal pin 73 which during the inward movement of the arm 68 of the lever 65 is engaged by said arm. The pin 69 normally bears against a pivotally adjustable stop arm 74 against which it is pressed by a spring-loaded stem 75 fitted in and movable radially with respect to the arbor 66.

The operation generally is as follows, clock-wise movements of the cams 63 and 64 being assumed:

The two arms of the levers 65 are of course moved in reverse directions. The drawings being considered, the arm 68 is moved left or inward and effects the movement of the plunger on its injection stroke. The arm 68 at a period of such inward movement engages the pin 73 and rocks the arm 71 outward or toward the right, the drawings being considered, against the pressure of the spring-loaded stem 75. By such movement of the arm 71 the pin 69 is shifted to the right

whereby the lever 54^a may move downwardly under the pressure of the spring 44 with resultant movement of the valve element 23 to its lower position and, the inward movement of the plunger continuing, any oil in the valve chamber 23 is returned as above described to the passage 21.

By adjustment of the pin 73 the period at which said pin is engaged by the arms 68 may be ordered and in this way the period at which the injection terminates may be regulated. The spring 28 acting through the plunger head 29 effects the return movement of the lever 65 and during such operation the end of the arm 70 rides on the recession surface of the cam 64 and the valve 25 is maintained in its lower position wherein the discharge passage 22 is cut off from the chamber 23 and said chamber through the passage 37 is open to the passage 21, oil at such time being drawn into the chamber 23.

By adjustment of the position of the stop arm 74 the point at which the injection commences may be regulated. By the movement of the eccentric 72 from the governor the duration of the rejection and hence the power is automatically regulated in accordance with the conditions.

It will be obvious that the details of structure and arrangement of the fuel injection pump may be varied or modified without departing from the principles of structure and operation described. It will also be obvious that the operating mechanism may be modified in respect to its details or even incorporated in forms substantially different from the forms shown. Hence the foregoing description of the specific features of the structures disclosed is not to be taken as imposing any limitation on the appended claims not inherent in their terms.

Having fully described my invention, I claim:

1. In a fuel injection pump for oil burning engines, in combination, a casing having an oil inlet passage, an oil discharge passage and a valve chamber intermediate said passages and formed with spaced seats communicating with the respective passages, a valve element in said chamber movable to different positions in which it has closing cooperation with the respective seats, said valve element having an operating part which projects beyond said casing, a pump chamber communicating with said valve chamber intermediate said seats and a pump element in said pump chamber.

2. In a fuel injection pump for oil burning engines, in combination, a casing having an oil inlet passage, an oil discharge passage and a valve chamber intermediate said passages and formed with opposed seats communicating with the respective passages, a reciprocatory valve element in said chamber having opposed valve faces to cooperate with

- the respective seats, said valve element having an operating part which projects beyond the casing, a pump chamber communicating with said valve chamber intermediate said seats and a pump element in said pump chamber.
3. In a fuel injection pump for oil burning engines, in combination, a casing having an oil inlet passage, an oil discharge passage and a valve chamber intermediate said passages and formed with spaced seats communicating with the respective passages, a spring loaded valve element in said chamber movable to different positions in which it has closing cooperation with the respective seats, said valve element having an operating part which projects beyond said casing, a pump chamber communicating with said valve chamber intermediate said seats and a pump element in said pump chamber.
4. In a fuel injection pump for oil burning engines, in combination, a casing having an oil inlet passage, an oil discharge passage and a valve chamber intermediate said passages and formed with opposed seats communicating with the respective passages, a spring loaded reciprocatory valve element in said chamber having opposed valve faces to cooperate with the respective seats, said valve element having an operating part which projects beyond the casing, a pump cylinder communicating with said valve chamber intermediate said seats and a spring loaded plunger in said cylinder.
5. In a fuel injection pump for oil burning engines, in combination, a casing having an oil inlet passage, an oil discharge passage and a valve chamber intermediate said passages and formed with opposed seats communicating with the respective passages, a spring loaded reciprocatory valve element in said chamber having opposed valve faces to cooperate with the respective seats, said valve element having an operating stem which projects beyond the casing, a pump chamber communicating with said valve chamber intermediate said seats and a pump element in said pump chamber and operating mechanism comprising a continuously rotatable shaft, a lever operated by said shaft for actuating said plunger, a second lever operated by said shaft for actuating said valve element against the pressure of its loading spring and means operative at a period of each revolution of said shaft for permitting the operation of said valve element by its loading spring.
6. In a fuel injection pump for oil burning engines, in combination, a casing having an oil inlet passage, an oil discharge passage and a valve chamber intermediate said passages and formed with opposed seats communicating with the respective passages, a spring loaded reciprocatory valve element in said chamber having opposed valve faces to cooperate with the respective seats, said valve element having an operating stem which projects beyond the casing, a pump chamber communicating with said valve chamber intermediate said seats and a pump element in said pump chamber and operating mechanism comprising a continuously rotatable shaft, a lever operated by said shaft for actuating said plunger, a second lever operated by said shaft for actuating said valve element against the pressure of its loading spring and means operative at a period of each revolution of said shaft for permitting the operation of said valve element by its loading spring.
7. In a fuel injection pump for oil burning engines, in combination, a casing having an oil inlet passage, an oil discharge passage and a valve chamber intermediate said passages and formed with opposed seats communicating with the respective passages, a spring loaded reciprocatory valve element in said chamber having opposed valve faces to cooperate with the respective seats, said valve element having an operating stem which projects beyond the casing, a pump chamber communicating with said valve chamber intermediate said seats and a pump element in said pump chamber and operating mechanism comprising a continuously rotatable shaft, two cams on said shaft, one cam serving for the actuation of said plunger, the other cam serving for the actuation of said valve element against the pressure of its loading spring, and means operative at a period of each revolution of said shaft for permitting the operation of said valve element by its loading spring.
- In testimony whereof I herewith affix my signature.

KRISTIAN RASMUSSEN.
